US00D912553S

(12) **United States Design Patent** (10) Patent No.: **US D912,553 S**
(45) Date of Patent: **** Mar. 9, 2021**

(54) **OPTOELECTRONIC SENSOR**

(71) Applicant: **SICK STEGMANN GmbH**,
Donaueschingen (DE)

(72) Inventor: **Michael Thurnherr**, Rapperswil (CH)

(73) Assignee: **SICK STEGMANN GMBH**,
Donaueschingen (DE)

(**) Term: **15 Years**

(21) Appl. No.: **29/689,825**

(22) Filed: **May 2, 2019**

(30) **Foreign Application Priority Data**

Nov. 6, 2018 (EM) 005818325-0008

(51) LOC (13) Cl. **10-05**

(52) U.S. Cl.

USPC **D10/75**

(58) **Field of Classification Search**

USPC D10/46, 75-80, 103, 104.1,
D10/106.1-106.95; D14/356, 357, 358,

D14/432, 433

CPC G01P 15/093

See application file for complete search history.

Meyer; Jerald L. Meyer

(57) **CLAIM**

The ornamental design for the optoelectronic sensor, as shown and described.

DESCRIPTION

FIG. 1 is a perspective view;

FIG. 2 is a top view;

FIG. 3 is a bottom view;

FIG. 4 is a front view;

FIG. 5 is a rear view;

FIG. 6 a left side view; and,

FIG. 7 is a right side view.

1 Claim, 6 Drawing Sheets

FIG. 1

FIG. 2

FIG. 3

FIG. 4

FIG. 5

FIG. 6

FIG. 7
